UNITED STATES PATENT OFFICE.

CHARLTON STANFORD AGATE, OF CHELMSFORD, AND PETER WILLIAM WILLANS, OF LONDON, ENGLAND, ASSIGNORS TO RADIO CORPORATION OF AMERICA, A CORPORATION OF DELAWARE.

RADIOSIGNALING.

Application filed September 28, 1921, Serial No. 503,797, and in Great Britain October 12, 1920.

This invention relates to means for controlling electric currents and for detecting or recording radio signals.

According to this invention two oscillatory circuits tuned to the same frequency are maintained in oscillation and are coupled to an untuned circuit. The latter circuit preferably consists of two coils one coupled to each oscillatory circuit or oscillator, and connected in series and across the filament and grid of a thermionic valve operating as a rectifier. The coupling of the third circuit to each of the oscillators should be close, while the coupling between the two oscillators should be as small as possible. In the anode circuit of the valve may be included an electro-magnetic relay or other device according to the purpose for which the invention is to be used. The valve is preferably arranged to work at a point on its characteristic where the grid current is small or zero. With such an arrangement it is found that the reaction of the current in the third circuit upon the oscillators is very small. When one or both of the oscillators is detuned in any way there is a considerable change of oscillating potential on the grid of the valve in the third circuit, which gives rise to a correspondingly considerable change in the anode current of this valve, which change in current is capable of actuating a relay, recorder or the like.

The invention is illustrated by the accompanying diagrams, in which:—

Fig. 1 is an illustration of an arrangement of circuits embodying the invention.

Figs. 2, 3 and 4 are illustrations of other embodiments of the invention.

Referring to Figure 1 A and B are two oscillation circuits in which oscillations are maintained by thermionic valves or according to any well known method, for example by the three electrode tube oscillation generators A', B' with suitable circuits. The third circuit consists of two inductances, D, D', closely coupled to circuits A and B, and connected in series with the grid and filament of a three electrode valve E arranged to operate as a rectifier. The circuit C is arranged to be well below resonance for the frequency of the oscillators, and a grid battery F is inserted and adjusted to prevent the flow of grid current. The

current in the third circuit is thus vanishingly small.

It is found that if A and B are tuned to exact resonance i. e. to the point in which no beats occur in circuit C, a very slight disturbance of the resonance conditions in either A or B gives rise to a considerable change of oscillating potential on the grid of the valve E which on rectification yields a corresponding change of direct current through a relay or galvanometer G, which may be advantageously connected in the plate circuit of valve E.

The apparatus may be employed for the purpose of controlling electric currents used for various purposes or recording radio signals by making the controlling agency or the signal throw one or other of the circuits A and B out of tune.

The change in tuning may be accomplished in various ways, for instance, the arrangement shown in conjunction with Fig. 1 may be employed. Here a small auxiliary condenser R' is shown connected in parallel to the condenser R of circuit A; as shown it consists of two plates H and I in close proximity to each other, one of which (H) is arranged to be susceptible of small mechanical displacements, for example, by means of a small electro-magnet O connected to a controlling agency. The plate H may be attached to or cooperate with any apparatus by whose motion it is desired to operate the relay G. Such an arrangement is particularly advantageous when it is desirable to avoid electrical contacts or to reduce the mechanical load on such apparatus.

For the purpose of recording radio signals an arrangement of the type shown in Figure 1 may be employed. The plate H is in this case a vibrating reed energized by the electromagnet O. The vibrating reed may be either aperiodic, i. e. of the nature of a telephone diaphragm, or it may be arranged to have a natural frequency corresponding to the note frequency of the signals, selective recording being thus possible. The recorder will be connected to the relay contacts. In either case a telephone may be inserted in addition to or in place of the relay.

If H and I are each capable of displacement along the same path and it is desired

to make the mechanism to which H is attached hunt the mechanism to which I is attached this can be effected by arranging that I is driven, for example, by a motor 5 G' under the control of the relay G, the motor being provided with a cam G'' for actuating the plate I. This feature is illustrated in dotted lines on Fig. 1. The frequency of the circuit A and therefore the 10 capacity between the plates H and I is thus kept constant and the plate H will hunt the plate I without touching it or putting any appreciable load upon it.

Instead of varying the tuning by a condenser the inductance of circuit A may be varied by a small mechanical displacement, say, of a variometer.

Since the frequency of oscillations in circuit A in general varies with change of 20 filament brightness in the maintaining valve (such variation being very sharp for suitable values of the components of the circuit) it is possible to operate the relay G by a change in the filament brightness of circuit 25 A, and thus to use the device as a voltage regulator.

In this case the auxiliary condenser R' or inductance is not necessary as the controlling agency is the source of E. M. F. 30 such as a current generator 1 (Fig. 2) which is connected to the filament of circuit A. This is maintained constant or controlled by the voltage regulator 2, which is operated by the relay G.

The relay can also be used to maintain 35 the frequency of oscillations of a transmitter constant. This is illustrated in Figure 3. Here the transmitter circuit A'' takes the place of the circuit A and variations of 40 the frequency of its oscillations are assumed to take place from any cause, say, the swinging of the aerial in the wind. The circuits B and C are arranged as before, and changes of current through the relay G 45 will take place when changes of wave length in A'' occur. The latter may be corrected by the arrangement shown. K is a variometer coil connected to circuit A'' and pivoted about a point K'. The coil is attached to 50 a lever L to the ends of which are attached the cores of two solenoids M, M, if necessary dashpots N, N may be attached to these cores to damp the motion of the variometer. The relay G has a neutral position and energizes one or other of the solenoids according as the current rises or falls. The 55 connections can be so arranged that this change of current produces an adjustment of the variometer coil K tending to counteract the change of wave length. Careful screening of circuit B from the direct influence of A is desirable. If the oscillations of A are not continuous but are broken up as in signaling advantage can be taken of 60 the fact that it is possible to adjust the ap-

paratus so that the relay current is the same whether the transmitter is inoperative or oscillating at its correct wave length.

Another method of recording continuous wave signals consists in superimposing the 70 high frequency signals upon the oscillations of A which will be tuned to approximately the same frequency. An effect is thereby obtained in circuit C as if the frequency of a wave changed. This superimposition may 75 be effected by coupling the source of signals (i. e. the aerial or the amplifier) electrostatically or electromagnetically to the circuit A, or else by the arrangement shown in Figure 4. Here the amplified high frequency signals are applied to the grid and filament of a valve P the plate and filament of which are connected to the plate and filament of the valve A' of A. With this arrangement the signals cause a change in 85 the relay current which can be used for recording purposes, the selectivity for wave length being very pronounced.

Having now described our invention what we claim is:—

1. In electrical controlling or indicating circuits, the combination of two oscillatory circuits tuned to the same frequency, means for maintaining oscillations therein, a current actuated controlling agency for changing the magnitude of the current in one of said oscillation circuits, an untuned circuit coupled to the two circuits and a relay actuated by currents in this third circuit to control or indicate changes in the controlling agency.

2. In electrical controlling or indicating circuits, the combination of two oscillatory circuits normally tuned to the same frequency, means for maintaining oscillations therein, a current actuated controlling agency for changing the magnitude of the current in one of said oscillation circuits, a third circuit coupled to the two circuits, means adapted to modify the currents of one of the first mentioned circuits and a relay actuated by currents in the third circuit to control or indicate changes in the controlling agency.

3. In electrical controlling or indicating circuits, the combination of two oscillatory circuits normally tuned to the same frequency, means for maintaining oscillations therein, a current actuated controlling agency for changing the magnitude of the current in one of said oscillation circuits, a third circuit coupled to the two circuits, means adapted to change the tuning of one of the first mentioned circuits and a relay actuated by currents in the third circuit to control or indicate changes in the controlling agency.

4. In electrical controlling or indicating circuits, the combination of two oscillatory circuits normally tuned to the same frequency, means for maintaining oscillations

therein, a current actuated controlling agency for changing the magnitude of the current in one of said oscillation circuits, a third circuit coupled to the two circuits, 5 a thermionic valve connected in said third circuit and a relay connected in the plate filament circuit of said valve to control or indicate changes in the controlling agency.

5. In electrical controlling or indicating 10 circuits, the combination of two oscillatory circuits normally tuned to the same frequency, means for maintaining oscillations therein, a current actuated controlling agency for changing the magnitude of the 15 current in one of said oscillation circuits, means for modifying the currents in one of the first mentioned circuits, a third circuit coupled to the two circuits, a thermionic valve connected in said third circuit and a 20 relay connected in the plate filament circuit of said valve to control or indicate changes in the controlling agency.

6. In electrical controlling or indicating 25 circuits, the combination of two oscillatory circuits normally tuned to the same frequency, means for maintaining oscillations therein, a current actuated controlling agency for changing the magnitude of the current in one of said oscillation circuits, 30 means adapted to change the tuning of one of the first mentioned circuits, a third circuit coupled to the two circuits, a thermionic valve connected in said third circuit and a relay connected in the plate filament circuit 35 of said valve to control or indicate changes in the controlling agency.

7. In electrical controlling or indicating circuits, the combination of two oscillatory circuits tuned to the same frequency, a variable impedance in circuit with the main 40 tuning elements of one of said circuits, means for maintaining oscillations in each of said circuits, an untuned circuit coupled to the two circuits, current-actuated controlling means cooperating with said variable 45 impedance and a relay actuated by currents in the third circuit.

8. In electrical controlling or indicating 50 circuits, the combination of two oscillatory circuits tuned to the same frequency, a variable condenser in circuit with the main tuning elements of one of said circuits, means for maintaining oscillations in each of said circuits, an untuned circuit coupled to the two circuits, current-actuated controlling 55 means cooperating with said variable condenser and a relay actuated by currents in the third circuit.

9. In electrical controlling or recording 60 circuits, the combination of two oscillatory circuits tuned to the same frequency, a variable condenser in circuit with the main tuning elements of one of said circuits, said condenser having two movable plates, means for maintaining oscillations in each of said 65 circuits, an untuned circuit coupled to the two circuits, a relay actuated by currents in the untuned circuit and means cooperating with said relay for causing one plate of the variable condenser to hunt the other plate.
